The ornamental design for a machine tool unit, as shown and described.

DESCRIPTION

FIG. 1 is a front left side perspective view of a machine tool unit showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings depict unclaimed environmental subject matter.

The machine tool unit is used for industrial manufacturing.
